SYSTEM FOR CARRYING EYEGLASSES
AND CELL PHONES

FIELD OF THE INVENTION

The present invention relates to a system for carrying eyeglasses and cell phones.

BACKGROUND OF THE INVENTION

Generally, when a person has an eyeglass holder or a cell phone holder a person utilizes a hard or soft case where she puts the eyeglass into the eyeglass holder or a cell phone into the cell phone holder. This case is usually a plain color, such as brown or vibrant color such as red or yellow. Usually, the eyeglass holder is not fashionable and is one standard shape. However, the unfashionable eyeglass holder or cell phone holder may not be appropriate for everyone. Therefore, there is a need for an improved system for holding eyeglasses or cell phones.

SUMMARY OF THE INVENTION

The present invention has been accomplished in view of the above-mentioned technical background, and it is an object of the present invention to provide a system for holding a pair of eyeglasses.

In a preferred embodiment of the invention, a system for holding a pair of eyeglasses, the system comprises: a first cloth fabric having a top rectangular portion, a middle portion and a bottom triangular portion; the bottom portion is folded over forward toward the middle portion, wherein the middle portion, includes an eyeglass holder portion configured to hold eyeglasses; the top rectangular portion configured to fold forward onto the middle portion; and the top triangular portion is attached to a leather strap, wherein the strap is configured to wrap around the first cloth fabric to hold the eyeglasses in the first cloth fabric.

In another preferred embodiment of the invention, a system for holding a cell phone is disclosed. The system includes: a first cloth fabric having a top portion, a front portion, a back portion and a bottom portion; the back portion of the first cloth fabric is connected to a back portion of a second cloth, wherein the second cloth is configured to receive and hold a cell phone; the top portion of the first cloth fabric is configured to attach to the bottom portion of the first cloth thereby holding the cell phone therein.

BRIEF DESCRIPTION OF THE DRAWINGS

These and other advantages of the present invention will become more apparent as the following description is read in conjunction with the accompanying drawings, wherein:

FIG. 1A is a top view of an illustration of a first embodiment of a system for carrying eyeglasses in accordance with the invention;

FIG. 1B is another view of an illustration of the first embodiment of a system for carrying eyeglasses in accordance with the invention;

FIG. 1C is another view of an illustration of the first embodiment of a system for carrying eyeglasses in accordance with the invention;

FIG. 1D is another view of an illustration of the first embodiment of a system for carrying eyeglasses in accordance with the invention;

2

FIG. 2A is a top view of an illustration of a second embodiment of a system for carrying eyeglasses in accordance with the invention;

FIG. 2B is another view of an illustration of the second embodiment of a system for carrying eyeglasses in accordance with the invention;

FIG. 2C is another view of an illustration of the second embodiment of a system for carrying eyeglasses in accordance with the invention;

FIG. 3A is a top view of a system for carrying a cell phone in accordance with the invention; and

FIG. 3B is another view of the system for carrying the cell phone in accordance with the invention;

15 DETAILED DESCRIPTION OF THE INVENTION

The presently preferred embodiments of the invention are described with reference to the drawings, where like components are identified with the same numerals. The descriptions of the preferred embodiments are exemplary and are not intended to limit the scope of the invention.

FIG. 1A is a top view of an illustration of a first embodiment of a system for carrying eyeglasses or eyeglass holder. Eyeglass holder 100 includes three portions a bottom portion 101, a middle portion 103, a top portion 105 and a tab 107. The tab 107 is utilized to attach the eyeglass holder 100 to a hook or ring inside of a typical bag, backpack or purse. Top portion 105 includes a typical hook and loop fastener (i.e. Velcro) 105a. Bottom portion 101 and top portion 105 have a trapezoidal shape but may have any type of shape, such as a rectangle, triangle or square. Eyeglass holder 100 may be made out of nylon, plastic, leather, silk or any kind of bendable material.

FIG. 1B is another view of an illustration of the first embodiment of a system for carrying eyeglasses where the bottom portion 101 is flipped horizontally onto the middle portion 103. FIG. 1C is yet another view of the first 40 embodiment of the system for carrying eyeglasses where the bottom portion 101 folds horizontally backwards onto the middle portion 103 where a hook and loop fastener (i.e. Velcro) 101a is shown. FIG. 1D is yet another view of the first 45 embodiment of the system for carrying eyeglasses where the top portion 105 is folded onto the bottom portion 101 where the hook and loop fastener (i.e. Velcro) 101a connects with the hook and loop fastener (i.e. Velcro) 105a of the top portion 105.

FIG. 2A is a top view of an illustration of a second 50 embodiment of a system for carrying eyeglasses or eyeglass holder. Eyeglass holder 200 includes a bottom portion 201, middle portion 203 and a top portion 205. The bottom portion 201 has a triangular shape but may have any shape, such as a rectangle, triangle or a square. Top portion 205 has 55 a trapezoidal shape but may also have any type of shape. Eyeglass holder 200 may be made out of nylon, plastic, leather, silk or any kind of bendable material.

FIG. 2B is another view of an illustration of the second 60 embodiment of a system for carrying eyeglasses. In this illustration that includes the eyeglass holder 200 with the bottom portion 201, middle portion 203 and the top portion 205, where the top portion 205 rolled onto the middle portion 203. FIG. 2C is another view of an illustration of the second embodiment of the eyeglass holder 200 where the top portion 205 that may include a pair of eyeglasses 209 is rolled into the middle portion 203 and bottom portion 201. Eyeglasses 209 may be the standard pair of eyeglasses or

sunglasses. The eyeglass holder 200 is then wrapped in a rope type material 207 to keep the eyeglasses secure in the eyeglass holder 200.

FIG. 3A is a top view of an illustration of a system for holding a cell phone or cell phone carrier. Cell phone carrier 300 includes a bottom portion 301, middle portion 303 and a top portion 307. Middle portion 303 includes a cell phone carrier holding compartment 305 that holds any size cell phone. Top portion 307 includes a hook and loop fastener (i.e. Velcro) 307a carrying eyeglasses or cell phone holder in 10 accordance with the invention;

FIG. 3B is another view of an illustration of the system for holding a cell phone/mobile phone where the bottom portion 301 is flipped horizontally onto the middle portion 303 and the top portion 307 with the hook and loop fastener (i.e. 15 Velcro) 307a may cover the mobile compartment 305.

This invention provides a worry free and simple system for holding a pair of Eyeglasses. The system includes: a first cloth fabric having a top rectangular portion, a middle portion and a bottom triangular portion; the bottom portion is folded over forwards toward the middle portion, wherein 20 the middle portion includes an eyeglass holder portion to configured to hold eyeglasses; the top rectangular portion configured to fold forward onto the middle portion; and the top triangular portion is attached to a leather strap, wherein 25 the strap is configured to wrap around the first cloth fabric to hold the eyeglasses in the first cloth fabric.

What is claimed is:

1. A system for carrying eyeglasses and a cellphone, comprising:

a single piece of material having a first front surface and a second back surface, said single piece of material including: a trapezoidal top portion; a rectangular middle portion; and a trapezoidal bottom portion;

wherein the single piece of material is a bendable material and the trapezoidal bottom portion is configured to fold onto the middle portion on said first front surface of the single piece of material, thereby forming a pocket configured to hold a pair of eyeglasses;

a first hook and loop fastener is coupled to the first front surface on the top trapezoidal portion;

a second hook and loop fastener is coupled to the second back surface of the bottom trapezoidal portion, wherein the first hook and loop fastener is configured to attach to the second hook and loop fastener when the trapezoidal top portion is folded onto the trapezoidal bottom portion;

a tab which forms a loop is coupled to and extends from a lower edge of the rectangular middle section, wherein the tab is configured to attach the system to a hook or ring inside a bag, a purse or a backpack;

a strap connected to and extending from the top trapezoidal portion, wherein the strap is configured to wrap around the entire system for carrying eyeglasses and a cellphone, and;

a cellphone compartment if formed on the second back surface of the rectangular middle portion, wherein said cellphone compartment is configured to hold a cellphone.

2. The system for carrying eyeglasses and a cellphone as claimed in claim 1, wherein the bendable material is selected from the group consisting of leather, rubber, felt, quilt fleece, 30 tapestry, nylon, plastic and silk.

3. The system for carrying eyeglasses and a cellphone as claimed in claim 1, wherein the strap is a leather strap.
